UNITED STATES PATENT OFFICE.

LOUIS LEGE, OF HANOVER, GERMANY.

TRACK-CLEANING DEVICE FOR STREET-TRAMWAYS.

SPECIFICATION forming part of Letters Patent No. 595,183, dated December 7, 1897.

Application filed October 7, 1896. Serial No. 608,174. (No model.)

To all whom it may concern:

Be it known that I, LOUIS LEGE, of 9 Braunschweiger Strasse, Hanover, in the Kingdom of Prussia, German Empire, have invented new and useful Improvements in Street-Tramways, of which the following is a specification, reference being had therein to the accompanying drawings.

The object of this invention is to provide a superior track-cleaning device of that class in which an instrument runs along the rail and has a part bearing thereon to scrape the accumulated matter from the rail.

The invention will be fully described hereinafter and defined in the claims.

Reference is to be had to the accompanying drawings, forming a part of this specification, in which similar characters of reference indicate corresponding parts in both the figures.

Figure 1 is a vertical longitudinal section of my invention, showing it applied to a car; and Fig. 2 is a plan view of the cleaner proper.

The cleaner is attached to the under side of the car-floor by means of a post p , the upper end of which has an annular groove p^2 , receiving a flange from a plate p' , bolted to the car. The post p is by these means mounted to turn freely on a vertical axis, but is held from other movement independent of the car.

Supported by the post p is the cleaner proper, which has a sheet-metal bottom plate a , carrying the longitudinal sides a' , which rise from the edges of the bottom plate and are curved inward at their front ends. The rear ends of the sides a' , respectively, run diagonally outward and rearward in conformity with the rearward arms o^2 of the bottom plate a . The edges of the arms o^2 opposite the edges having the sides a' are provided with sides a^2 , extending upwardly, similar to the sides a' . The central front portion of the bottom plate a is formed with a recess b , while the forward portion of the cleaner is beveled, as at b^2 , so that when the cleaner occupies the inclined position shown in Fig. 1 the beveled portion will run along the tread of the rail.

Secured to the under side of the bottom plate a and running longitudinally from the rear portion thereof to a point forward of the body portion is a scraper-tongue o' , which is located directly beneath the recess b of the bottom plate a , so that when the scraper is in the

position shown in Fig. 1 the tongue o' will project into the groove of the rail. Attached to the sides a' is a transverse bar g , by which the cleaner proper is pivotally connected to the lower end of the post p . It is thus that the cleaner proper is mounted to swing either to the operating position shown by full lines in Fig. 1 or to the inoperative position shown by dotted lines in the same figure.

Formed on a bar t , secured to the bottom of the car, is a bell-crank lever t^2 , to one end of which a connection t^3 is attached and to the opposite end of which a link t^4 is attached. The link projects downwardly and is secured to the middle portion of the side a^2 . By these means the cleaner may be raised to the position shown in Fig. 1. The manner in which the cleaner is mounted is such that the rear portion of the cleaner will have a preponderance, tending to throw the cleaner to the position shown by dotted lines in Fig. 1. Consequently when the tension on the connection t^3 is relaxed the cleaner will automatically assume an inoperative position.

The cleaner is shown here in connection with a rail having a central groove and a tread on each side of the groove. It is clear, however, that the invention may be used in connection with other forms of rails which have a groove receiving the flange of the wheel.

Having thus described my invention, I claim as new and desire to secure by Letters Patent—

1. A track-cleaner having a receptacle adapted to receive material from the track, the receptacle having two rearwardly and outwardly extending branches for delivering the said material, the branches running oppositely to each other and delivering the material respectively on the sides of the track, and a tongue carried by the receptacle and projecting forwardly thereof, the tongue being capable of running in the groove of the rail so as to deliver material from said groove to the receptacle, substantially as described.

2. A track-cleaner having a receptacle formed of a bottom with rearwardly and oppositely extended delivering branches projected respectively on opposite sides of the track, the front portion of the bottom having a recess, a tongue secured to the bottom and projecting past said recess so as to deliver

material into the receptacle through the recess, and sides secured to the edges of the bottom and arising therefrom, substantially as described.

- 5 3. The combination of a plate having a curved flange, a post with an annular groove received by the flange whereby the post is mounted to turn, and a track-cleaner carried by the post, substantially as described.
- 10 4. A rail-cleaner having a receptacle or body portion capable of discharging material

laterally therefrom, and a tongue projecting forward from the receptacle or body portion and capable of running in the groove of a rail to remove material therefrom and carry the material to the receptacle or body portion.

In witness whereof I have hereunto set my hand in presence of two witnesses.

LOUIS LEGE.
